MEANS FOR BALANCING ROTARY PUMPS

George H. Zenner and Edward F. Kendall, Kenmore, N. Y., assignors to The Linde Air Products Company, New York, N. Y., a corporation of Ohio

Application April 11, 1941, Serial No. 388,048

7 Claims. (Cl. 103—112)

This invention relates to means for balancing forces in rotary pumps, and particularly to means for balancing the reactive forces, due to the outlet pressure in multi-stage turbine pumps when arranged for pumping a highly volatile liquid, such as liquefied gas having a boiling point temperature at atmospheric pressure less than 273° K., for example, liquid oxygen.

The invention has for its object generally the provision of an improved arrangement of pumping elements for balancing the pressure in rotary type pumps whereby liquids, particularly volatile liquids of the character indicated, may be pumped and discharged against relatively high heads of pressure without employing high values of the unit loading on the bearings.

More specifically, the invention has for its object the provision of an arrangement for pumping liquid oxygen in a plurality of stages against heads of pressure of moderately high value, for example, against heads up to 400 lbs. per square inch gauge, by rotary elements using self-lubricating bearings without undue wear on the bearings and without incurring undue leakage between stages.

Another object is to provide a multi-stage turbine pump with a rotary element carrying axially displaced sets of pumping blades with an arrangement for readily achieving the desired centering in operation of the blades without undue friction and without the need for precise pre-adjustment of clearances.

Another object is to provide a multi-stage turbine pump for pumping liquid oxygen with a common shaft for the rotating elements journaled in bearings of bonded graphite, the journals being arranged to be self-centering.

Still another object is to provide a casing for a multi-stage pump of the character indicated with a pressure chamber arranged to equalize the bearing pressures on opposite sides of the shaft carrying the rotor element so as to compensate for unequal reactive forces on the bearings, whereby a turbine pump having a relatively long operating life and requiring little servicing is provided.

Other objects of the invention will in part be obvious and will in part appear hereinafter.

The invention accordingly comprises the features of construction, combination of elements, and arrangements of parts, which will be exemplified in the construction hereinafter set forth, and the scope of the invention will be indicated in the claims.

For a fuller understanding of the nature and

objects of the invention, reference should be had to the following detailed description taken in connection with the accompanying drawings, in which:

- 5 Fig. 1 is a vertical sectional view of a two-stage turbine pump, adapted for pumping a volatile liquid such as liquid oxygen, in which the second stage is divided to achieve balancing in accordance with the invention;
- 10 Fig. 2 is a view, mainly in end elevation but partly in section, showing the conduit connections of the pump shown in Fig. 1;
- 15 Fig. 3 is a vertical sectional view which shows a modification of the invention in which balancing is achieved by the use of a special chamber;
- 20 Fig. 4 is another end elevational view with parts broken away to show sectionally certain details of the balancing chamber used in the modification of Fig. 3; and
- 25 Figs. 5 and 6 are explanatory diagrams.
- The principles which apply to the pumping of a volatile liquid, such as a liquefied gas with boiling point temperature at atmospheric pressure materially below 273° K., are taught in U. S. Patent to Thompson, No. 1,930,731, patented October 17, 1933. Here, a first stage is provided in which the liquid is discharged against a relatively low head but the pressure is sufficiently raised to achieve what in effect is subcooled liquid supplied to the second stage where the liquid being pumped may be discharged against relatively high heads of pressure. In rotary type pumps, when it is necessary to pump against relatively high heads of pressure, the multi-stage pump is resorted to; the advantage being that the liquid impellers of the several stages may be mounted on a single shaft and driven from a single source of mechanical power.

Referring now to the drawing, and particularly to Figs. 1 and 2, a two-stage or compound turbine type pump is shown by way of illustrating a rotary pump in which balancing is achieved in accordance with the invention; balancing being desirable in multi-stage pumps by reason of the relatively high discharge heads against which they work, whereas in single-stage pumps, by reason of their relatively low discharge heads, unbalance is generally of a negligible order. Here a pump casing, shown generally at 10, is formed of interfitting members 110, 111, 112, and 113; members 110 and 113 being closures for the casing proper, member 110 having a central opening closed by a plate 11 which carries a tubular extension 12. This latter serves as a housing for 35 an entering shaft 13 that carries the rotary

pumping elements. Shaft 13 has an enlargement at the inner end, as shown at 130 (that may be keyed to the shaft 13 by a key 16) and runs in a bearing bushing 15, held in place by a closure plate 17. The latter element is directly secured to the member 113 which has a boss or hub 14 formed to support plate 17. Any suitable securing means, such as bolts 18, may be employed. The assembled casing members may likewise be secured together by means of bolts, as shown at 19 and 19'.

The bushing 15 is preferably of a solid self-lubricating material, such as a bonded graphite. The other end of shaft 13 is passed to the exterior through extension 12 for receiving driving power, in any suitable manner known to the prior art, for example, as shown in Fig. 3, as hereinafter more fully explained.

The member 111, when closed by member 110, is arranged to provide a pumping channel for the first stage, the pumping channel being denoted 120 and provided with a rotary liquid impeller or turbine wheel 20. The working margin of wheel 20 is arranged to clear the walls of channel 120 by a considerable space. Members 111 and 112 are likewise arranged to provide a second stage, or pumping channel denoted 121, while another channel 122 is provided by the members 112 and 113. Channels 121 and 122 in effect constitute a divided second stage, and their combined cross-sectional area is arranged to accommodate the liquid discharged by the first stage. In each of the channels 121 and 122 second-stage impellers, denoted 21 and 22 respectively, are disposed in working relation and mounted on shaft 13, together with impeller 20 to comprise a single rotor for the pump. To this end, each of the impellers is shown as having a hub, denoted 20', 21', and 22' in the drawings, which is keyed to the shaft 13. Each of these hubs is arranged to run between thrust bearings of substantially the same material as the bearing bushing 15, and at least one such thrust bearing may be adjustably mounted in the casing 10, in order to maintain proper centering for the impellers (the specific showing of any such adjusting means being omitted in the interest of simplicity). Impeller 20 is accordingly shown running between bearing rings 24 and 25, the latter of which is carried by a suitably formed recess in the casing member 111 for receiving the same. Similar constructions are provided for centering impellers 21 and 22. The casing 10 has a supporting base; any convenient supporting means may be used; webbed legs being shown at 10b by way of example.

The unbalanced effect here considered is the resultant of the reactions from the liquid pressure distributed about the periphery of the impeller. Such reactions are in a generally radial direction but increase from the inlet to the outlet of the channel in which the impeller works, the force diagram of the same being graphically shown in Fig. 5 where it is seen there is a large unbalanced portion which gives a resultant R which may be considered as a force concentrated at some point in the pumping channel; for example, one concentrated at a point displaced from the outlet of the pumping channel by an angle of approximately 90°. To achieve a balancing of such resultant, the second stage of the two-stage pump may be divided, or another stage may be added, as shown, for example, in Fig. 6, where three channels are depicted at a, b, and c, respectively. The last channel is connected to

channel b by a conduit d. Channel c provides another resultant which is arranged to be directly opposed to that otherwise had from channel b, so as to balance it.

5 The unbalanced force can be balanced in several ways: (1) by using two second-stage impellers in parallel as shown in Figs. 1 and 2 of this invention with the suction and discharge ports of one impeller diametrically opposite from those of the other impeller. In this case the unbalanced force from one impeller will exactly balance the force from the other impeller. (2) By using a cylinder mounted on the pump shaft, one-half the periphery of the cylinder being in a 15 region of high pressure and the other half being in a region of lower pressure. The cylinder proportions are then chosen such that the differential pressure acting over its periphery will balance the force from the second-stage impeller. (3) By using a three-stage pump, as 20 shown diagrammatically in Fig. 6. The three-stage arrangement also contemplates the employment of valves in the connections of the channels, for example, that shown at e in the connection d and that shown at f in a by-pass connection g which may be provided about the 25 last stage, as indicated in Fig. 6. By manipulating such valves, a proper balance may always 30 be obtained.

These valves afford considerable flexibility in 35 this respect. In general, opening of valve f permits fluid to bypass the stage c and correspondingly to reduce the resultant unbalanced force in stage c as the opening at valve f is increased. Under most conditions valve e will be fully open but it may be employed where desired to produce 40 modification of the balancing effects. As valve e is closed the discharge from stage b will be constricted, increasing the discharge pressure in stage b and increasing correspondingly the unbalanced force in that stage. Simultaneously the constriction in the inlet to stage c will tend to 45 reduce the inlet pressure to stage c and this may effect a reduction in the unbalanced resultant in stage c. This latter may in turn, however, be varied by adjustment of valve f as described 50 above.

55 The divided stage arrangement is shown in Fig. 1, and is seen to comprise pumping channels 121 and 122, which may have their inlets and outlets so disposed that the resultant of one channel opposes that of the other and a balanced effect achieved. To this end, the arrangement of the channels 121 and 122 in the casing 10 is such that the inlet channels thereto are on substantially opposite sides of the casing, the outlets being similarly disposed. Conduits for receiving 60 the discharge from the outlet of the first stage, dividing the same and leading the portions to the two second-stage inlets, are accordingly associated with the casing 10. External conduits are advantageous and conducive to compactness 65 in casing construction and are shown in Fig. 2.

In Fig. 2, the inlet connection for the first channel is shown at 116 and is relatively large since it is connected to a low pressure source of supply of the volatile liquid to be pumped. Such 70 inlet connection leads into the channel 120 by a

channel that is streamlined, as taught in co-pending application, Serial No. 345,308, filed July 13, 1940, in the name of O. A. Hansen. The outlet connection from the first stage is at 117 at a point in the top half of the casing relatively close to the inlet 116, which is here shown as leading into the lower half. Outlet connection 117 has a dividing nipple or T-connection 118 from which lead conduits 119 and 119' The first leads across the top of the casing 10 to an inlet connection 126 that leads to one of the second-stage pumping channels (here taken as 121) while the conduit 119' leads across the side of the casing to the other second-stage inlet (here taken as that for channel 122) denoted 126'. Both inlets 126 and 126' are streamlined and are located at substantially diametrically opposite points in the casing 10.

The outlet from the first-named second-stage pumping channel is at 127, that for the second-named second-stage pumping channel at 127'. These outlets are, by the arrangement here employed, also at substantially diametrically opposite points on casing 10. A conduit at 128 receives the discharge from the channel 121 and leads across under the casing to discharge into a union T-like coupling 129 that is placed to receive directly the discharge from channel 122. Here the liquid from the two pumping channels of the second stage is united and discharged at a high pressure, such as 400 p. s. i. gauge, into a common conduit or other receiver.

In operation, it is seen that the pressures at both the inlets and the outlets of the channels of the divided second stage are so placed as to offset one another and hence a balanced reaction is achieved.

In Figs. 3 and 4, another modification is disclosed, using a pressure chamber adapted to apply pressure to counteract the unbalance directly to a rotatable shaft, here denoted 13', which carries the first-stage and second-stage impellers 31 and 32. The impellers are shown running in first- and second-stage pumping channels 321 and 322 formed in a casing generally similar to that at 10, but having only two stages and here denoted 10''. Pumping channel 321 has an inlet at 316 and an outlet at 317, while channel 322 has an inlet 326 and an outlet 327. Outlet 317 is connected to inlet 326 by an exterior conduit 320, as shown in Fig. 4.

Here the casing 10'' is composed of three interfitting members 310, 311, and 312, the latter of which has a boss 314 closed by a member 315 that supports a bushing bearing 15' for the shaft 13'. The other end of casing 10'' has a plate 11 and extension 12 arranged as above described. The shaft 13' is shown having an enlargement 30 to which the impellers 31 and 32 are keyed. The inner smaller end of shaft 13' is enlarged by a sleeve member 330, keyed thereto and arranged to run in the bushing bearing 15'. Member 330 has an enlarged flange portion 325 comprising a piston member that runs in a pressure chamber 323 formed in the boss 314. Such chamber is divided into non-communicating portions by ribs 51 and 52 which extend axially out from the wall of chamber 323 a distance such as just to clear the cylindrical wall of portion 325. The uppermost chamber portion 323'' is connected by a channel 55, provided as a bore in the casing extending from the portion 323' into the outlet 327, while the lowermost portion 323' merges through a passage 50 directly into the hub chamber of impeller 32.

There is also shown in Fig. 3, by way of example, a gland for the outer end of shaft 13'; such gland being for use with a compression packing in a stuffing box (the complete showing of the packing material and the stuffing box being omitted from the drawings in the interests of clearness of illustration. In general the gland illustrated comprises a carbon bushing 43 in a sleeve 44, that avoids galling and is held in place by means of a nut 45 which is secured in any suitable manner, for example, by screwthreaded engagement, as shown.

By reference to the arrangement, as shown in Fig. 4, it is seen that outlet pressure is conveyed through channel 55 to the chamber portion 323'' which is positioned in the channel somewhat in advance of the outlet 327. There is a balancing force, in consequence, exerted on the shaft 13' due to the presence of this chamber, which force is substantially at right angles to a line passing through the center of the shaft and the outlet. This force is seen to counteract that which results from the gradual increase in pressure around the pumping channel, such increase being graphically shown in Fig. 5. The pump casing here employed may, if desired, be provided with peepholes leading to the pumping channels of the first and second stages for inspection purposes, and normally closed by plugs, as shown at 109.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described our invention, what we claim as new and desire to secure by Letters Patent is:

1. In a multi-stage rotary type pump, the combination with a casing provided with a plurality of pumping channels each having separate inlet and outlet channels, of a driving shaft journaled in said casing, a plurality of bladed impellers having their working circumferences arranged for running respectively in said pumping channels mounted on said shaft and forming therewith a rotor for the pump, conduit connections effecting working communication between said inlets and outlets, bearings associated with said casing for said shaft, and a balancing chamber in said casing having a cylindrical element cooperatively associated with said shaft adapted to apply force thereto; said chamber having communication with a point of relatively high pressure in said channels and arranged so as to expose a portion only of said element in the circumferential direction to said high pressure, the remaining circumferential area being exposed to a lower pressure and said chamber being so located angularly about said shaft whereby there is provided a radial force operating upon said shaft in magnitude and direction to counteract substantially the resultant arising from the gradual increase of pressure around the periphery of said rotor.

2. In a multi-stage rotary type pump, the combination with a casing provided with a plurality of pumping channels each having separate inlet and outlet channels, of a driving shaft journaled in said casing, a plurality of bladed impellers having their working circumferences arranged for running respectively in said pumping channels mounted on said shaft and forming therewith a rotor for the pump, conduit connections

effecting working communication between said inlets and outlets, bearings associated with said casing for said shaft, an enlargement on one end of said shaft running in said casing, and a balancing chamber formed about said enlargement and divided into portions in the circumferential direction, each of said portions having communication with a source of pressure taken from selected points in said connected channels and arranged to provide a resultant for balancing that arising mainly from the gradual increase of pressure around the periphery of the last stage of said rotor.

3. In a multi-stage rotary type pump, the combination with a casing provided with a plurality of pumping channels each having separate inlet and outlet channels, of a driving shaft journaled in said casing, a plurality of bladed impellers having their working circumferences arranged for running respectively in said pumping channels mounted on said shaft and forming therewith a rotor for the pump, conduit connections effecting working communication between said inlets and outlets, bearings associated with said casing for said shaft, and a balancing means in said casing comprising a rotatable element mounted on said shaft and provided with a circumferential channel in said casing, said last-named channel having communication with said last-stage pumping channel and extending over a part of the area only of said element in the circumferential direction which gives a force counteracting that arising mainly from the gradual increase of pressure about the periphery of the last stage of said rotor.

4. In a rotary pump the combination with a casing, a driving shaft journaled in said casing, rotary fluid impeller means mounted on said shaft and adapted to operate in said casing, an auxiliary drum-like member mounted on said shaft, a fluid chamber formed about and extending over a portion only of said member in the peripheral direction, connections for admitting fluid to said chamber from the fluid discharge side of the pump, and means for exposing a radially opposing part of the periphery of said member to a lower pressure, the arrangement and proportions being such as to produce a net radial force on said member of a character and direction to counteract the resultant of the radial forces acting on said fluid impeller means from the pumping action.

5. In a multi-stage rotary pump the combination with a casing, a plurality of bladed impellers operating in pumping channels in said pump, fluid-conduit means for connecting said impeller means in series, a driving shaft journaled in said casing for supporting and operating said im-

pellers, a drum-like counterbalancing member mounted in said casing on said shaft, a fluid chamber formed about and extending over a portion only of said member in the peripheral direction, connections for admitting fluid to said chamber from the discharge of the high pressure stage, an opposing part of the periphery of said member being exposed to a lower pressure and the arrangement and proportions being such as to produce a net resultant radial force on said member counter to the resultant of the radial forces acting on said high pressure stage impeller from its pumping action.

6. In a rotary pump the combination of a casing, a driving shaft mounted therein and extending outwardly therefrom, a pumping channel in said casing and a rotary impeller mounted on said shaft operative in said channel, the inner end of said shaft terminating in and being completely enclosed within said casing and provided therein with a radial bearing of solid self-lubricating material, a fluid chamber adjacent the periphery of said inner end restricted to a portion only in the circumferential direction thereof, a fluid connection from the pump discharge to said chamber for applying such pressure to said inner end over a limited area in the peripheral direction, and means connecting a limited peripheral area at the opposite side of said shaft to a point of lower fluid pressure, the arrangement being such as to produce a net radial force on said shaft in a direction to counteract the resultant of the radial forces acting on said fluid impeller from the pumping action.

7. In a rotary fluid pump, the combination of a casing, a driving shaft journaled in said casing, rotary fluid impeller means mounted on said shaft and adapted to operate in a pumping channel in said casing, the pumping action producing a resultant radial force on said impeller acting in a certain direction, a radial bearing in said casing for one end of said shaft, a fluid chamber associated with said bearing adjacent the periphery of said shaft end restricted to a portion only in the circumferential direction thereof, a fluid connection to said chamber for exposing it to the pressure of the pump discharge and thereby applying such pressure to the shaft over a limited area in the peripheral direction, and means connecting a limited peripheral area at the opposite side of said shaft to a point of lower fluid pressure, the arrangement being such as to produce a net radial force on said shaft in a direction to counteract the said resultant force from the pumping action.

GEORGE H. ZENNER.
EDWARD F. YENDALL.
